(57) **CLAIM**

The ornamental design for a combined portable storage container and interior shelf, as shown and described.

DESCRIPTION

FIG. 1 is a top, front and side perspective view of a first embodiment of a combined portable storage container and interior shelf embodying the new design shown in an unassembled state.

FIG. 2 is a top, rear, and side view thereof.

FIG. 3 is a front view thereof.

FIG. 4 is a back view thereof.

FIG. 5 is a side view of the container component, the opposite view being a mirror image thereof.

FIG. 6 is a side view of the shelf component, the opposite side view being a mirror image thereof.

FIG. 7 is a top view of FIG. 1 with the handle in a folded configuration.

FIG. 8 is a bottom view thereof.

FIG. 9 is a top, front and side perspective view of a second embodiment of a combined portable storage container and interior shelf embodying the new design shown in an assembled state.

FIG. 10 is a top, rear, and side view thereof.

FIG. 11 is a front view thereof.

FIG. 12 is a back view thereof.

FIG. 13 is a side view thereof, the opposite side view being a mirror image thereof.

FIG. 14 is a top view of FIG. 9 with the handle in a folded configuration; and,

FIG. 15 is a bottom view thereof.

The portable storage container and interior shelf are disclosed separately for convenience of illustration. The broken lines illustrate unclaimed portions of the article.

The dash-dot-dash broken lines illustrate the boundary of the claimed design.
